Application December 2, 1935, Serial No. 52,452
In Austria December 3, 1934

5 Claims. (Cl. 179—36)

In telephone systems in which alternating current impulses are transmitted over the connecting line care has to be taken that the transmission of alternating current, which passes over the line in both directions during the call and brings about switching operations at both ends of the connecting line, takes place systematically so that the alternating current impulses do not proceed simultaneously thereby preventing important 5 switching operations from taking place.

This systematic operation cannot be observed, however, when telephone systems having subscribers provided with magneto ringing are involved in which unforeseen alternating currents 10 may be transmitted at all stages of the call.

The invention resides in that, in systems in which alternating current impulses are sent out from an exchange and which have subscribers' stations provided with magneto operation, the 15 transmission of individual alternating current impulses (seizing and releasing impulses) effected by the exchange, which are of importance for the call and which control connecting devices, is delayed in the event of the subscriber transmitting 20 alternating current either simultaneously with or partly before the impulse transmission, during the time thus occupied by the magneto current.

A further characteristic of the invention resides in that in the exchange devices, only alternating 25 current impulses sent out by the exchanges involved are operative, dependent on their duration and sequence, and that the duration and sequence of the alternating current impulses passing over the connecting line are supervised in the connecting devices by means of relay combinations.

The drawing represents an embodiment of the invention. A system is shown for communicating from subscribers connected to a party line who are provided with local battery and magneto stations in which all calls including internal calls 30 are set up in a semi-automatic manner by way of a further exchange by means of alternating current impulses transmitted by the operator back over a connecting line. All those details 35 which are not necessary in order to understand the invention, such as the relay repeater device which connects the individual subscribers with one another and with the exchange line, are omitted.

40 It will be assumed that one of the subscribers desires a connection with another subscriber of the same local exchange or group. Since the establishment of all calls is only semi-automatic he must call up the communicating or main exchange over the connecting trunk line.

The call is set up by the transmission of alternating current from the magneto of the calling subscriber whereupon the speaking leads of the subscriber are switched through on to the leads 5 *a* and *b* in the relay repeating device which is not shown since it is not essential for understanding the invention. The alternating current sent out by the subscriber energizes the alternating current relay *W3* which switches the line through at contacts *37w3* whereupon the drop *FK* associated with the cut-off jack *K1* is also operated over the connecting line *VLtg* which terminates in repeating coils *U1* and *U2*. The operator of the connecting exchange is thereby informed of the existence of the call and inquires by plugging into 10 the jack.

The drop *FK* is disconnected by the plug and the jack contacts *13kli* operated. The following switching operations take place: Relay *D* energizes over earth, *13kli*, *11w1*, *10a1*, *W1*, *D*, and 20 battery, whereupon relay *E* energizes over earth, *30d* and *W12*, and the relay *F* over earth, *32e*, *W14*, *F*, and *W13*. The adjustment of relays *D*, *E*, and *F* over resistances *W1*, *W12*, and *W14* is such that these relays, which are moreover provided with 25 a copper sleeve over the core, energize relatively slowly. From the operation of the jack contacts *13kli* until the energizing of relay *F*, relay *R1* remains energized. It energizes in the circuit: 30 earth, *13kli*, *11w1*, *10a1*, *8d*, *7a2*, *6f*, *R1*, and battery, and locks up, after the opening of contact *8d*, at contact *9r1* until it is disconnected by contact *6f*. Over contacts *27r1* and *28r1* an alternating current seizing impulse is applied to the connecting line throughout the time during which 35 relays *D*, *E*, and *F* are energized. By means of this impulse relay *W2* is energized over the line. Contact *54w2* of relay *W2* causes relay *G* to energize over contact *53k*. This relay energizes relay *H* by means of contact *57g* and the latter relay 40 brings up relay *K* over contact *56h*. Contact *53k* disconnects relay *G* again and locks up relay *K* until contact *54w2* opens. Contact *38k* disconnects the speaking line. Relays *G* and subsequently *H* make a delayed release. When the 45 seizing impulse comes to an end relay *H* still remains energized after relay *W2* releases since the seizing impulse only lasts during the energizing period of three relays (*D*, *E* and *F*), so that now relay *B* energizes over earth, *44w2*, *45b(2)*, *46h*, *50* *W15*, *B*, and battery. Relay *B* is constructed as a two-stage relay and on being operated over *W15* only operates contact *47b(1)*. The contacts operated when the relay is fully energized bear the index "(2)". After the release of relay *H* relay *B* 55

establishes a locking circuit, earth, 48rt, 47b(1) in which it energizes fully on account of W15 having been short circuited at 46h. The speaking line is switched through by means of contact 36b(2). 5 Contact 42b(2) seizes the relay repeater device over the c-lead in a corresponding manner.

If the subscriber transmits alternating current by operating his magneto while the plug is inserted in the jack, the transmission of the seizing impulse does not take place until relay W1 deenergizes again, since this relay energizes and opens contact 11w1. Relays D, etc. then energize over contacts 13kli, 11w1, etc. whereupon relay R1 is energized transitorily, etc. as has already been described. 10

After the enquiry on the part of the operator the latter dials impulses over the line, since the subscriber desires a connection with the subscriber of the same group. It is assumed that 20 the impulses transmitted over the line do not operate directly upon the connecting device of the subscriber on account of their relatively high frequency, but are registered in the relay repeating device and are given out again more slowly.

25 The registering device in the relay repeater is connected up by the operation of the a key on the part of the operator, closing contacts 19ET and 35ET. Relay A1 is energized in the circuit earth, 19ET, A1, A2I and battery. Relay A2 receives insufficient current through its winding A2I, and does not energize. Relay R1 energizes again over earth, 1a1, 2a2 and 6f until relay F, which is short circuited by 35ET, deenergizes. After the release of the key comprising contacts 19ET and 35ET 30 35 relay A1 locks up over earth, 13kli, 15a1, A2II, A1, A2I and battery, and relay A2 now energizes since both its windings are subjected to current. Relay F likewise energizes slowly over the resistance W14 and the other operations take place 40 as described earlier so that meanwhile relay A2 becomes energized.

When now relay R1 is switched over again it can no longer energize since contacts 1a1 and 2a2 are operated. Contacts 21r1 and 28r1 connect 45 alternating current transitorily to the line so that relay W2 energizes and brings up relay G by means of contact 54w2. Relay H energizes over 50 55 51g and relay K over 56h. Relay R2 does not energize in response to this brief impulse over earth in the relay repeater, lead e, 51b(2), 50k and 49w2 since it is provided with means (a copper slug fitted to the core) making it slow to energize. The earth connected over 60w2 and lead f is likewise inoperative before the registering device in the relay repeater has been connected up. The registering device is connected up after the release of relay W2, over earth, 44w2, 45b(2), 43h and the line d. Contact 43h is still operated since the relays release slowly one after 60 the other, after relay G has been disconnected. The operator can be informed over the speaking line that the connection has taken place, by means of an audible signal, so that the depressing of the key comprising contacts 19ET and 35ET 65 can be repeated if for any reason the connection does not take place, for example on account of a simultaneous transmission of alternating current on the part of the subscriber. On the connecting up of the registering device the speaking line 70 is cut off in the relay repeater so that the transmission of alternating current on the part of the subscriber can no longer be a source of disturbance.

The desired number is now dialled and is taken 75 up by the registering device of the relay repeater.

The dial impulse contact 5nsi energizes relay R1 intermittently over 5nsi and earth. Contacts 21r1 and 28r1 connect alternating current to the line and relay W2 is energized intermittently. The impulses are transferred to the registering device over earth, 60w2 and the lead f. During dialling relays G, H, and K hold up throughout the impulse trains. Relay R2 cannot energize while dialling is in progress since the lead e is disconnected in the relay repeater. 10

When the registering device has been set the impulses are released by the operation of a key comprising contacts 21AT and 34AT. Since relays A1 and A2 are still energized, relay A2 holds up throughout the time during which the key is depressed, over earth, 21At and 20a2, while relay A1 is short circuited and releases. Relay R1 is accordingly again energized over 1a1, 2a2 and 6f and transmits an impulse over contacts 21r1 and 28r1. The impulse is limited by contact 6f, for 20 relay F is short circuited over 33a1 and 34AT and deenergizes. After the release of the key relay A2 deenergizes and relay F becomes energized. The release period of relay A2 is smaller than the energizing period of relay F so that relay R1 is 25 not again energized. By means of the alternating current impulse relay W2 is energized transitorily and operates relay G over 54w2, the latter relay brings up relay H at contact 51g and this in turn energizes relay K over 56h. The alternating current impulse of the same duration as that causing the registering device to be connected up cannot energize relay R2 which is slow to energize. An additional setting in the registering device by way of contact 60w2 is thus prevented. 30 On the termination of the impulse earth is again connected to the d-lead over contacts 43h, 45b(2) and 44w2, whereby the impulse transmission is released in the relay repeater. The operator receives an audible signal over the line until the 40 impulse emission has terminated. 35

Subsequently the speaking line is again switched through in the current repeater to the subscriber, the latter being called by the transmission of ringing current over the jack Kli. This transmission of ringing current is more prolonged than the controlling impulses so that relay R2 energizes over earth in the relay repeater, lead e, 51b(2), 50k, and 49w2, and transmits the ringing current over contacts 40r2 and 41r2 to the subscribers who are now both called. 45

The clearing signal is given by one of the two subscribers by means of the magneto, whereupon relay W3 energizes and disconnects relay W2 at contact 37w3. In addition to the clearing a drop in the supervisory cord circuit is operated, whereupon the plug is withdrawn and the jack contact 13kli is switched back to normal. Current passes through relays A1 and A2 over earth, 13kli, 17L, and 18d. The two relays energize simultaneously so that contacts 1a1 and 2a2 are switched over without relay R1 having been energized. Relay L energizes over earth, 13kli, 22w1, 24a2, and 26d, and disconnects relays A1 and A2 at contact 17L. Relay A2 deenergizes rapidly but relay A1 makes a delayed release. Meanwhile relay R1 is energized over earth, 1a1, 2a2, 6f, R1 and battery and connects alternating current to the line at contacts 21r1 and 28r1. After the release of relay A2 the L relay holds up over earth, 13kli, 22w1, 23f, 25L until relay F deenergizes on the completing of the release. Contact 10a1 disconnects relay D, 30d disconnects relay E and 32e relay F. Over contacts 3e, 4d and 6f relay R1, which has in the meantime released, again 50 55 60 65 70 75 80 85 90 95 100

becomes energized. Meanwhile, a second impulse is transmitted over the line. Thus, for the purpose of release, two relatively short impulses separated from one another by an interval corresponding to the release period of two relays are transmitted over the line. Relay W2 is energized twice. Contact 39w2 disconnects relay W3 and the relay repeater. On the first energizing of relay W2 relay G energizes. Contact 51g energizes 10 relay H, and 56h relay K. Relay G holds up over 54w2 and 52b(2). After the impulse the relays G, H, and K release in succession. When the second impulse occurs relay K has not yet deenergized and relay RT is energized. Contact 48rt 15 disconnects relay B and the release is effected by 42b(2). All the subsequent operations in the relay repeater have no bearing on the invention and will not further be described.

In the event of the subscriber transmitting alternating current from his magneto while the plug is being withdrawn, relay W1 is energized and prevents the release by means of contact 22w1. Meanwhile contact 14w1 holds relay A1 energized over contact 15a1 and the latter relay 25 holds up relay D over 10a1. After relay W1 deenergizes the release proceeds as already described.

What is claimed is:

1. In a telephone system, a local exchange having magneto lines, a main exchange connected 30 to said local exchange by a trunk line, means responsive to a call from a magneto line for signalling the operator at said main exchange by transmitting alternating current over said trunk line, means controlled by the main exchange 35 operator for transmitting alternating current back over said trunk line to said local exchange to establish a connection with the calling magneto subscriber, and means automatically operated for delaying the transmission of the alternating current by the operator controlled means 40 in the event that the calling magneto subscriber transmits further alternating current at the time the connection is being established by the operator.

2. In a telephone system, a local exchange having magneto lines therein, a main exchange connected to said local exchange over a trunk line, means responsive to a call from a magneto line for transmitting alternating current over said 50 trunk line to signal the main exchange operator, means controlled by the main exchange operator for transmitting an alternating current impulse back over said trunk line to said local exchange to establish a talking connection with the calling line, and means in said main exchange for automatically delaying the transmission of the alternating current impulse to the local exchange 55

in case the calling magneto line transmits additional alternating current.

3. In a telephone system as claimed in claim 2 in which the local exchange is provided with switching equipment controlled by the transmission of alternating current seizing, connecting, and releasing impulses from the main exchange, and in which the transmission of any of said impulses is automatically prevented as long as the calling magneto line sends further alternating 10 signalling current.

4. In a telephone system, a local exchange having magneto lines, a main exchange connected to said local exchange by a trunk line, means responsive to a call from a magneto line for signalling the operator at said main exchange by transmitting alternating current over said trunk line, means controlled by the main exchange operator for transmitting alternating current seizing, connecting, and releasing impulses of 20 only a particular duration and sequence back over said trunk line to said local exchange, switching equipment at said local exchange responsive to said alternating current impulses for establishing a connection with a desired magneto subscriber, and means for delaying the transmission of the alternating current impulses by the operator controlled means in the event that the calling magneto subscriber transmits further alternating current which is of a different duration and sequence at the same time or partly before said impulses are transmitted by the operator controlled means to establish a connection.

5. In a telephone system, a local exchange having magneto lines therein, a main exchange connected to said local exchange over a trunk line, means responsive to a call from a magneto line for transmitting alternating current over said trunk line to signal the main exchange operator, 40 a relay chain combination in said main exchange controlled by operator for transmitting alternating current seizing, connecting, and releasing impulses of a definite duration and sequence back over said trunk line to said local exchange, switching equipment at said local exchange responsive to said alternating current impulses for establishing a connection with a wanted local exchange magneto line, and means in said main exchange for temporarily delaying the transmission of said alternating current impulses by said relay chain combination in the event that the calling magneto line transmits additional alternating current of different duration and sequence at the same time said other impulses are being 50 transmitted to said local exchange.

FRIEDRICH LILL.
